DRAINAGE FOR ROOFS AND SKYLIGHTS

Filed June 19, 1930

FIG. 2.

UNITED STATES PATENT OFFICE

ARNO SHUMAN, OF PHILADELPHIA, PENNSYLVANIA, ASSIGNOR TO PENNSYLVANIA WIRE GLASS COMPANY, OF PHILADELPHIA, PENNSYLVANIA, A CORPORATION OF NEW JERSEY

DRAINAGE FOR ROOFS AND SKYLIGHTS

Application filed June 19, 1930. Serial No. 462,164.

The principal object of the present invention is to provide good drainage from the inside to the outside of a roof or skylight for moisture which may condense on the inner surface of the roof. Another object of the invention is to accomplish the result indicated without the employment of long gutters.

Generally stated, the invention may be said to comprise a crimped plate arrangement under the felt on which the overlying glass is laid so as to provide channels between the felt and the underlying glass or other support through which the water of condensation passes from the inside face of the overlying sheet onto the outside face of the underlying sheet.

The invention also comprises the improvements to be presently described and finally claimed.

In the following description reference will be made to the accompanying drawing forming part hereof and in which

Figure 1 is a sectional view taken cross-wise of the purlins and illustrating features of the invention.

Fig. 2 is a perspective view of a crimped plate embodying features of the invention.

Fig. 3 is a transverse sectional view taken on the line 3—3 of Fig. 1, and

Fig. 4 is a similar view taken on the line 4—4 of Figure 1.

In the drawing 1 indicates a crimped plate which may be made of appropriate metal or material. The plate is provided with anchors 2 and, as shown, they are of the form of hooklike legs. 3 indicates purlins upon which the underlying sheets 4 of corrugated glass are supported. The overlying sheets 5 of corrugated glass in Fig. 3 rest upon a strip of felt or the like 6, which in turn rests upon the underlying sheets of glass 4. In the structure shown in Fig. 4, the sheets of glass 4 rest upon a filler strip 7 conforming to the corrugations in the glass, and it is supported upon a strip of felt 6 which in turn rests upon a purlin 3. Incidentally it may be said that the devices 8 and 9 prevent the glass from sliding endwise off the roof, and the device 10

The crimped or corrugated plate or element 1 underlies the strip of felt or the like 6 and rests upon the underlying sheet of glass, Fig. 3, over the upper edge of which the anchors 2 engage and then pass between the purlin 3, Fig. 1, and the under face of the underlying sheet. As shown in Fig. 4 the anchors 2 engage directly with the purlin 3, and the crimped portion of the plate overlies the flashing.

The mode of operation may be described as follows:

The plates 1 in spaced relation are embedded in the felt and the crimps provide open passages indicated at 11. Water of condensation on the inner face of the sheet of glass 5 at the righthand in Fig. 1, runs out through the passages 11 onto the outer face of the underlying sheet of glass 4, and water of condensation from the under face of the sheet 4 runs out through passages 11 at the left in Fig. 1 outside of the flashing 10. In this way good and efficient drainage is provided.

It may be remarked that the anchors 2 provided on the crimped plate 1 are spaced apart and arranged at the side edges near one end of the plate and when this is done they serve their purpose as anchors without interfering with the drain passages 11.

In referring to felt or the like in connection with the element 6, the intention in both the specification and claims is to include any material into which the crimped elements 1 may be embedded in substantially the manner described.

The strips 6 and fillers 7 may be spaced from the top edges of the purlins, and when this is done pockets 12 are provided between the strips, purlins and underface of the glass, and these pockets may accumulate moisture of condensation which finds its way to the outside by the channels 11.

It will be obvious to those skilled in the art to which the invention relates that modifications may be made in detail of construction and arrangement and matters of mere form without departing from the spirit of the invention which is not limited to such matters or otherwise than the prior art and the appended claims may require.

I claim:

1. For roofs or skylights having a strip of felt upon which corrugated glass is laid, drainage means comprising a crimped plate arranged under the felt strip and providing drain channels, said crimped plate having at one end marginally arranged spaced hooklike legs engaging the roof structure, the crimps in said plate extending in a direction parallel to the axis of the hooked portion of said legs.
2. In a sloping roof or skylight structure the combination of a corrugated sheet of glass, a support for the corrugated sheet of glass, a felt strip interposed between the support and sheet of glass, and a crimped plate embedded in the strip of felt and providing drainage channels, the crimps in said plate sloping parallel to said roof.
3. In a sloping roof or skylight structure the combination of a corrugated sheet of glass, a support for the corrugated sheet of glass, a felt strip interposed between the support and sheet of glass, and a crimped plate embedded in the strip of felt and providing drainage channels, said crimped plate having anchors that engage the support and the crimps in said plate sloping parallel to said roof.
4. In a sloping roof or skylight structure the combination of purlins, strips superposed on and spaced from the top edge of the purlins, corrugated sheets of glass supported on the strips, there being pockets provided between the tops of the purlins and the glass and the strips for the accumulation of moisture of condensation, and crimped plates arranged on top of the purlins and under the strips providing drainage from the pockets, the crimps in said plates sloping parallel to said roof.
5. In a sloping roof or skylight structure the combination of purlins, corrugated sheets of glass supported on said purlins and spaced therefrom, there being provided pockets between the tops of said purlins and said glass for the accumulation of moisture of condensation, and crimped plates having longitudinal crimps therein sloping parallel to said roof arranged between said purlins and said glass to provide drainage from said pockets.

ARNO SHUMAN.
